Fleming & Flemming,
Attorneys.

UNITED STATES PATENT OFFICE.

VALENTY WROCLAWSKI, OF CHICAGO, ILLINOIS.

FREIGHT-CAR.

1,322,212.

Specification of Letters Patent. Patented Nov. 18, 1919.

Application filed May 29, 1919. Serial No. 300,596.

To all whom it may concern:

Be it known that I, VALENTY WROCLAWSKI, a citizen of the United States of America, and a resident of Chicago, county of Cook, and State of Illinois, have invented certain new and useful Improvements in Freight-Cars, of which the following is a specification.

The main objects of this invention are to 10 provide an improved construction for freight cars, having the ends thereof shiftably mounted so as to yield to pressures created by the relative shifting of the load and the car; to provide an improved arrangement of resilient means for holding 15 said end members in place; and to provide an improved construction of said resilient means and connection thereof with said end members.

20 An illustrative embodiment of this invention is shown in the accompanying drawings, in which—

Figure 1 is a longitudinal sectional elevation of a box car, the ends of which are 25 yieldingly supported in place in accordance with this invention.

Fig. 2 is a fragmentary transverse sectional detail of one end of the car.

Fig. 3 is a bottom plan, on a larger scale, 30 of one of the shock-absorbing devices by which the lower parts of the car ends are held in place.

Fig. 4 is a bottom view of the housing for 35 the shock-absorbing devices used in the upper part of the car.

In the construction herein shown, the invention is applied to a wooden box car, but it will be readily understood that it is 40 equally applicable to freight cars of the gondola or open type, and to cars of metal construction.

As illustrated in the drawings, the car is 45 provided with end wall members 1 and 2 shiftably mounted within the sides, bottom, and top and abutting against frames 3. These end wall members are normally retained in place against the frames by shock-absorbing devices at the top and bottom of the car to which said end members are connected.

50 Each of the shock absorbing devices comprises a pair of plates or followers 4 and 5 shiftably mounted in a suitable housing and normally urged apart by a heavy compression spring 6. Rods 7 and 8 connect the followers 4 and 5 with the respective end

members 1 and 2, whereby the springs 6 normally urge the end members inwardly against the frames 3.

The preferable construction of the housing for supporting the shock absorbers on the bottom of the car comprises a pair of castings having interfitting end flanges 9 and 10 and side flanges 11, by means of which the housing is bolted to the framework of the car. The preferable form of the housing used in the top of the car is that shown in Fig. 4, which consists of a hollow casting open at the bottom, through which the plates 4 and 5 and the spring 6 may be 60 passed for the purpose of being assembled within the housing. End flanges 12 are formed on the housing, by means of which the housing is bolted to the framework of the car. 75

Apertures 14 are formed in the ends of the housing through which the rods 7 and 8 pass, and inasmuch as said rods are connected to the followers which are the more remote from the respective end members, eccentrically disposed apertures 15 are formed 80 in the followers 4 and 5, through which passes the rod not connected to the corresponding follower. As shown in Fig. 3, the rods are offset at their ends so as to be connected centrally to their respective followers. 85

Braces or plates 16 are secured to the end members 1 and 2 and extend upwardly and inwardly respectively for a considerable distance from the rods 7 and 8, so as to distribute the strain throughout a considerable portion of the respective end members. 90

The housings for the lower shock absorbers are located under the bottom of the car between adjacent beams 17, being secured 95 in place by bolts extending through the flanges 11. The housings for the upper shock absorbers are secured to the sides of the car adjacent to the roof, being secured in place by bolts extending through the flanges 12. 100

A yielding end construction for railroad cars is particularly needed for the shipment of lumber and other loosely piled articles, for the reason that during transit the violent jars to which the load is subjected result in a relative shifting of parts of the lumber and the car. Where the ends of the car are rigid, this relative shifting of the load results in puncturing, breakage, or even 105 total destruction of the end walls. When the end walls are equipped with the herein- 110

described shock absorbers, relative shifting of the load and car will merely cause the ends to yield temporarily and will be followed by a more or less normal restoration 5 of the load under the influence of the springs 6 as the car continues to travel.

Although but one specific embodiment of 10 this invention has been herein shown and described, it will be understood that numerous details of the construction shown may be altered or omitted without departing from the spirit of this invention as defined by the following claims.

I claim:

- 15 1. A car of the class described, comprising shiftably mounted end wall members, shock absorbing mechanism located intermediate the ends of said car, and means connecting said end members with said shock absorbing 20 mechanism whereby said end members are normally urged toward each other.
- 25 2. A car of the class described, comprising shiftably mounted end wall members, shock absorbing mechanism located at the top and the bottom of said car intermediate its ends, and means connecting said end members with said shock absorbing mechanism whereby said end members are normally urged toward each other.
- 30 3. A car of the class described, comprising shiftably mounted end wall members, shock absorbing mechanism located intermediate the ends of said car, and rods connecting said end members with said shock absorbing 35 mechanism whereby said end members are normally urged toward each other.
- 40 4. A car of the class described, comprising shiftably mounted end wall members, shock absorbing mechanism located at the top and the bottom of said car intermediate its ends, rods connecting the shock absor-

ing mechanism in the bottom of said car with the lower part of said end members and the yielding mechanism in the top of said car with the upper part of said end 45 members, and braces on said end members extending inwardly from their point of connection with said rods.

5. A car of the class described, comprising shiftably mounted end wall members, a 50 housing located intermediate the ends of said car, a pair of followers slidably arranged in said housing and connected to the respective end members, and yielding means normally acting on said followers to 55 normally urge the respective end members inwardly toward each other.

6. A car of the class described, comprising shiftably mounted end wall members, a 60 housing located intermediate the ends of said car, a pair of followers shiftably mounted in said housing, resilient means normally urging said followers away from each other, and a rod connecting each of said followers with the respective end member which is 65 the more remote therefrom, whereby said end members are normally urged toward each other.

7. In a car, movable end walls at opposite ends of the car, a helical spring located intermediate said end walls and extending lengthwise of the car, followers engaging opposite ends of said spring, and a pair of rods extending from the opposite end walls through the spring and being connected respectively to the said followers which are most distant from their respective end walls, whereby a single spring will absorb shocks at either end of the car.

Signed at Chicago this 21st day of May, 80
1919.

VALENTY WROCLAWSKI.
